UNITED STATES PATENT OFFICE

LOUIS W. REINHARDT, OF BROCKTON, MASSACHUSETTS, ASSIGNOR TO GEORGE E. BELCHER COMPANY, OF STOUGHTON, MASSACHUSETTS, A CORPORATION OF MASSACHUSETTS

DISPLAY FORM

Application filed June 6, 1925. Serial No. 35,434.

In the vending of certain articles of apparel it has been found most advantageous to display the garment as worn on a figure or member so that it will appear in its normal state of presentation or, if possible, one even more attractive, so that merchandising may be stimulated by a faithful or, if possible, flattering suggestion of appearance.

The presentation of articles of nether apparel in such a manner has proven difficult, but in logical conclusion has come to a display upon an artificial or model limb.

This has developed a serious problem between the province of the sculptor and the manufacturer.

Obviously, the resultant article or limb model must be so artistic as to provide the incentive to purchase. It must also be a cheap and ready article of merchandise.

Wooden legs have been turned and other more convenient and artistic models attempted. I believe my own production is complete and novel and has proven by immediate popularity, a filling of a long felt want.

A part of the difficulty has been productability, a part lightness and convenience and a part mechanical adaptability to the purpose of display.

In producing a display model for hosiery the problem is to derive from the suitably sculptured model a commercial form artistically satisfactory and sufficiently cheap to permit its use in merchandising.

The ordinary wooden leg is classically impossible. A clean-cut, beautifully modeled, esthetically finished form is required. Another phase of the problem has been that of supporting such a display member and in so doing without destroying the natural effect of the limb member. This requirement has doubtless inspired the previous suggestion of a sole engaging stand but the presence of a stocking on the form makes such a support difficult to effect.

I will describe a product in accordance with my invention, which is capable of commercial production but which may carry a merchandising persuasiveness, as has been demonstrated in practical use.

To illustrate such a device, I have shown

a form in the accompanying drawing. To this, the specification makes reference by conventional characters. In these drawings:

Fig. 1 is a general view of a form as in display. 55

Fig. 2 is a longitudinal section of the foot and base.

Fig. 3 a transverse section of the same, and Fig. 4 a section as used without base. 60

Instead of providing a turned or cast solid form, I provide a moulded shell-like form of fibre or like stock. This gives a hollow model which is of immediate value as light and convenient. It is also capable of a variety of usages and practices not heretofore possible. 65

In this form as shown, I provide a moulded shell modeled to the figure and comprising so much of a nether limb as may be required. 70

As shown, I have illustrated a foot 1, a lower leg 2 and an upper leg portion 3. These are formed of sheet stock fibre moulded over a carefully prepared model form. As such, they are light, ventilated and capable of very attractive commercial presentation. The mounting of such an article is difficult, as is the dressing. The device must be disposable in show window or on show case. It must also receive and skillfully display the article, such as a stocking, in perfect presentation of its best possible appearance. 75 80

It will be understood that while the upper limb may be successfully enlarged in the model to give full effect, the foot cannot be made larger than normal. This makes a problem in the case of an unsymmetrical limb. The stocking must fit the wearer, but the model must not admit the irregularity. 85

Furthermore, the model must be supported or held upright to give the living or lifelike effect. To provide for this, as well as to accomplish the impossible in the previously stated requirement of compensation, I have devised a simple structure. 90 95

My foot form 1 is hollow as moulded from stock and open at the bottom.

This gives me a possibility of reception of surplus foot stock of the hose displayed on the form. In addition, I utilize it as a me- 100

chanical asset by providing a base 4 and a cleat 5.

The cleat 5 is of simple T-shaped form. It may be interlocked with the hollow foot form 1, not only to support the form, but to draw tight, the stocking (or other article) over the form to make a perfect and attractive fit.

At its upper end (of whatever length) the form is left partially open so as to receive any excess of stocking, lingerie or other drapery, required to set off the model. For example, the slack in the foot of the stocking may be taken up through this opening in the sole by inserting a clip member 6 which is turned sidewise to engage the flange 1¹ which surrounds the edge of the foot sole. This is depended upon where the form is not used on its usual stand or where it is to be removed from the stand for inspection. I further provide for this taking up of slack by utilizing the interlocking device of my base 4.

The interlocking of the cleat 5 by the simple turning of the foot 1 on it, gives, therefore, both physical support and artistic drapery to the stocking foot which will be shown as fitting at its best.

The model is light and easy to carry. It is easily manufactured by moulding such material as board about a form, fitting, gluing and joining to give a complete shell. This may be painted and finished so as to give the representation of the natural limb at its best. Also, it provides the best possible means of display mounting.

Various modifications may be made. Such devices may be variously manufactured. All I desire by my present application is protection commensurate by my claim.

What I therefore claim and desire to secure by Letters Patent is:

In a display form including in combination a foot having a hollow portion and an opening in the sole of the foot communicating with the hollow portion, and a base having means thereon for supporting the form and locking said form in position so as to prevent removal by any relative lateral or longitudinal movement between the base and the form, said locking means including a post and a locking member thereon adapted to enter the opening in the sole of the foot, said locking member having a length greater than the width of the opening in the foot and being so disposed relative to the opening in the sole as to require relative rotary movement from the normal display position of the form between the display form and the base in order to pass the locking member through the opening in the sole of the foot, whereby when the form is normally positioned on the base the locking member assumes a position within the foot crosswise of said opening in the sole of the foot.

In testimony whereof I affix my signature.

LOUIS W. REINHARDT.
